UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

RADIO SIGNALING SYSTEM.

Application filed May 4, 1918. Serial No. 232,589.

To all whom it may concern:

Be it known that I, ERNST F. W. ALEXANDERSON, a citizen of the United States, residing at Schenectady, county of Schenectady, State of New York, have invented certain new and useful Improvements in Radio Signaling Systems, of which the following is a specification.

My present invention relates to radio signaling systems and particularly to a transmitting system in which continuous radio frequency current is employed for producing signals.

When a source of continuous radio frequency current such as an oscillating arc has been employed for signaling purposes, it has been the usual practice to produce signals by varying the tuning of the antenna and thereby varying the frequency or wave length of the transmitted wave. This method has one marked disadvantage over a system in which the signal is produced entirely by intensity variations of the transmitted wave, in that it may result in interference with other stations which operate on a slightly different wave length.

The object of my invention is to provide a transmitting system in which the signals transmitted will be produced entirely by variations in the intensity of the antenna current.

In carrying my invention into effect I make use of a controlling device which is based on the principle of magnetic saturation. Devices of this type, which I term magnetic amplifiers, are described in my prior U. S. Patent No. 1,206,643. Assuming that the antenna is the fundamental tuned circuit, I have found that a magnetic amplifier may to advantage be made a part of a second tuned circuit which is associated with the antenna circuit, and that by this arrangement a much wider range of change in impedance may be produced than when the amplifier is directly included in the antenna circuit. The magnetic amplifier of the general type described in my prior U. S. patent has been found to be well suited for the control of high frequency generators of fixed frequency, such as an alternator. When, however, it is attempted to use a magnetic amplifier to control a source of high frequency, the frequency of which is indefinite and depends

upon the tuning of the system, there are 55 certain difficulties which must be overcome.

A more specific object of my present invention is to provide a system in which these difficulties will be obviated. Since the frequency of the current depends upon the capacity and inductance of the circuit, it is apparent that a system which produces a variation in the intensity of the current must act to vary the effective resistance of the antenna circuit, or the electromotive 60 force of the source of supply or both simultaneously in such a way that intensity variations may be produced without introducing frequency variations. In other words, the inductance and capacity of the antenna 70 circuit should remain substantially constant. If a magnetic amplifier were introduced in series with the antenna, as shown in my prior patent above referred to, this would not be the case, since in the operation of the device a wide variation of resistance is always accompanied by a wide variation of inductance, the variations depending upon the degree of saturation produced by the controlling current. If a second tuned circuit alone is used a similar difficulty will exist. In order to overcome these difficulties I provide a third tuned circuit which may be designated as a tertiary circuit, the antenna tuning being the 75

primary and the tuning of the magnetic amplifier proper being the secondary. Neglecting for a moment the antenna tuning, the combined controlling device which I provide and which is made up of one or more magnetic amplifiers, will of itself have a double tuned characteristic, one of the tuning points being the original tuning circuit of the magnetic amplifier, the other tuning point being produced by the combination of the magnetic amplifier circuit and other devices which make up the tertiary tuning circuit. Broadly speaking, a condition of tuning is one where the inductance and capacity of a circuit neutralize each 80 other at a certain frequency, that is, the complete circuit is apparently a non-reactive circuit for that frequency. A double tuned circuit becomes non-reactive under two sets of conditions. These conditions are usually defined by saying that the circuit becomes non-reactive at two frequencies. Inasmuch as the object of the present invention is to 85 90 95 100 105

design a system which operates only at a single frequency, the nature of the invention may be best explained by saying that the combined controlling circuit is double 5 tuned with reference to different degrees of saturation of the magnetic amplifier involved, rather than with reference to two different frequencies. In other words, the object is to produce a combined circuit 10 which becomes non-reactive at two different values of the controlling current used for saturating the magnetic amplifier unit or units involved.

In one modification of my invention in 15 which a single magnetic amplifier is employed, the circuit is so designed that for two different values of the saturating current the circuit becomes non-reactive and between these values the inductance increases 20 to a maximum and then decreases. There will be, however, a considerable range between these two values of saturating current over which the variation in inductance will be less than the effective resistance of the 25 antenna, while at the same time the effective resistance of the circuit will be varied by an amount much greater than the effective resistance of the antenna. By the term "effective resistance" as used herein, I mean 30 the electromotive force in phase with the current at the specified frequency, required to force one ampere of current through the circuit.

In another form of my invention in which 35 two magnetic amplifiers are employed forming two secondary circuits, the tertiary circuit is formed by a combination of the two secondary circuits. In this case the controlling circuit is substantially non-reactive 40 throughout the entire operating range.

The novel features which I believe to be characteristic of my invention are set forth with particularity in the appended claims. The invention itself, however, both as to its 45 organization and method of operation will best be understood by reference to the following description taken in connection with the accompanying drawing in which Figure 1 shows the first modification of my 50 invention above referred to, and Figs. 2 and 3, respectively, show two different circuit connections whereby the second modification of my invention may be carried into effect.

55 As indicated in the drawings, the source of continuous radio frequency current employed in my transmitting system comprises the arc 1, which is supplied with direct current for its operation from the direct 60 current generator 2, the usual inductances 3 and 4 being included in the circuit. The arc 1, in the system indicated in Fig. 1, is connected in series with the antenna 5, which is provided with the usual tuning inductance 6. In series in the antenna cir-

cuit I provide a variable inductance or magnetic amplifier 7 of the general type described in my U. S. Patent No. 1,206,643. In the specific form here shown the device 70 comprises windings 8 and 9 which are in parallel in the antenna circuit and the current for saturating the magnetic core is derived from direct current generator 10, being supplied to the windings 8 and 9 in series by means of a key 11. The amplifier 7 is shunted by 75 a capacity 12 and resistance 13.

If the condenser 12 is given such a value as to neutralize the inductance of amplifier 7 at the operating frequency when its core 80 is not saturated the control circuit becomes non-reactive and the resistance of the portion of the circuit which includes the amplifier will depend only upon the value of the resistance 13. If now a saturating current is applied to the windings of amplifier 7, the inductance will change and the resistance of the antenna circuit will no longer be determined by the value of resistance 13 but 85 will depend upon the value of the inductance of the amplifier. While the actual value of the amplifier inductance will gradually decrease, its effect as an inductance in the antenna circuit will increase with an increase in the saturation current from zero 90 up to a maximum value and will then decrease until it is neutralized by the series condenser 14. The inductive effect of the amplifier in the antenna circuit will then be zero but the resistance of the antenna circuit will be much less than when the core is 95 unsaturated. In this case the combination of the magnetic amplifier 7 with the series condenser 14 forms the secondary tuned circuit and the capacity 12 in combination with the amplifier 7 forms the tertiary tuned circuit. 100

I have found that there is a fairly wide range between the two points where the effect of the inductance of the amplifier in the antenna circuit is zero, over which 105 its value does not vary enough to materially affect the natural frequency of the antenna circuit. In order to take advantage of this range a constant saturating current may be supplied to the amplifier windings of such a value as to bring the value of the amplifier inductance in the antenna circuit to a point in the desired operating range where the antenna resistance is high. The value of 110 this current, which may be supplied by generator 10, may be adjusted by means of the variable resistance 15. The circuit which supplies the controlling current is also preferably so adjusted that when the key 11 is closed to short circuit the resistance 15 the 115 value of the amplifier inductance in the antenna circuit will still be within the desired range but the antenna resistance will be greatly decreased. The two values of saturation current may be so selected that the 120 125 130

antenna inductance will be the same when the key is pressed as when it is open and hence the natural frequency of the antenna circuit will be the same when the current therein is a maximum as when it is a minimum. In any case, however, the system may be so adjusted that the variation in inductance over the operating range chosen will not be great enough to materially vary the natural frequency of the antenna circuit and at the same time the antenna resistance may be varied sufficiently to secure an effective modulation of the current.

In the arrangement shown in Fig. 2, condenser 16 is employed in shunt to the arc, and in shunt to the condenser 16, I provide a second variable inductance, or magnetic amplifier 17, of the same type as device 7. When the controlling circuit is in the condition shown in the drawing the key 11 being closed at 18, the intensity of the current in the antenna 5 will be a minimum. Under these conditions the inductance of amplifier 17 is small and the inductance of amplifier 7 is large. The inductance of amplifier 7 is neutralized by the capacity 12 in shunt therewith in the same way as in Fig. 1, when the key 11 is open, so that the secondary circuit formed by amplifier 7 and the inductance 12 becomes substantially non-reactive but forms a high impedance in the antenna circuit. At the same time the inductance of amplifier 17 is neutralized by the large capacity 16 so that the resultant secondary circuit also becomes substantially non-reactive and the loop 16, 17, 14, forms an absorption circuit. When it is desired to transmit telegraphic signals key 11 is operated to close the contact at 19 and open the contact at 18. The inductance of 7 then becomes small and is neutralized by the capacity 16 in series therewith. Consequently the control circuit is again in effect non-reactive but the effective resistance is much less than when the key is closed at contact 18.

When the key 11 makes contact at 18, the resulting impedance for the circuit formed by amplifier 17 and capacity 14 as well as that circuit formed by amplifier 7 and capacity 12 is substantially non-reactive. When the key is shifted to make contact at 19 the resultant impedance of the circuit formed by amplifier 17 and capacity 14 becomes inductive and the resultant impedance of the circuit formed by amplifier 7 and capacity 12 becomes capacitive. The resultant inductive impedance of the first circuit, however, neutralizes the resultant capacity impedance of the second circuit.

The arrangement which I have illustrated in Fig. 3 differs from that shown in Fig. 2 in that the capacity 16 instead of being in shunt with the arc is in series therewith. The operation of the system, however, will

be substantially the same as that of the one shown in Fig. 2 with the exception that in this case as soon as the impedance of the control system becomes large there will be a marked falling off in the arc current, whereas in the arrangement shown in Fig. 2 the arc current will be diverted to the secondary absorption circuit formed by amplifier 17 and capacity 16 instead of flowing through the antenna. Because of this characteristic it will be desirable to employ a condenser 21 in shunt to the arc to prevent the arc current from being entirely interrupted.

In the arrangement of Fig. 3 when the key 11 is in the position shown the inductance of 17 is neutralized by capacity 16 and the inductance of 7 is neutralized by capacity 12. Hence both of these loops 16, 14, 17 and 12, 7 offer a high impedance to the flow of current in the antenna. When the key 11 is shifted the loop 16, 14, 17, becomes in effect an inductive impedance and the loop 12, 7 becomes a capacity impedance. The resultant inductive impedance of loop 16, 14, 17 is neutralized by the resultant capacity impedance of loop 12, 7 which is in series therewith. The combination of the two loops therefore becomes non-reactive and offers a low impedance to the flow of current in the antenna.

In utilizing my amplifiers in the manner described it is necessary that condensers 20 be inserted in the closed circuit formed by the windings 9 and 10. These condensers should have such value as to offer a low impedance to the high frequency current but a high impedance to the controlling current.

While I have shown and described three different ways in which my invention may be carried into effect, I do not wish to be limited to the particular circuit arrangements shown as it will be apparent that many variations may be made in the various details and in the form of the apparatus used without departing from the scope of my invention as set forth in the appended claims. For example, while I have shown and described my invention with particular reference to the use of an oscillating arc as a source of radio frequency energy, its utility is by no means limited to this particular current source as other sources of supply may equally well be employed in carrying my invention into effect.

What I claim as new and desire to secure by Letters Patent of the United States, is,

1. The combination in a radio signaling system of an antenna circuit supplied by a source of continuous radio frequency current and a control system associated with said antenna circuit, said control system comprising an inductance which is variable by magnetic saturation and means for vary-

ing the inductance to produce a substantial change in the effective resistance of the control system and at the same time maintain its resultant reactance substantially 5 constant.

2. The combination in a radio signaling system of an antenna supplied by a source of continuous radio frequency current, means for varying the amplitude of the current in said antenna comprising a magnetic controlling device, and means for varying effective resistance of said amplitude varying means by a value greater than the effective resistance of the antenna while 10 the accompanying variations of reactance are less than the effective resistance of the antenna.

3. The combination in a signaling system of an arc generator, an absorption circuit and a signaling circuit associated therewith and a single control means for simultaneously varying in opposite senses one of the constants of each of the two circuits.

4. The combination in a signaling system of an arc generator, an absorption circuit and a signaling circuit associated therewith and a single control means for simultaneously varying in opposite senses one of the constants of each of the two circuits, 25 said means being adapted to substantially prevent the flow of current in the signaling circuit during the intervals between signals.

5. Means for controlling the flow of radio frequency current in an electric circuit comprising a variable inductance having a shunt and a series capacity associated therewith, the capacities being so chosen that at one value of the inductance it is 30 neutralized by the series capacity at a desired frequency and at a second value of the inductance it is neutralized by the shunt capacity at the same frequency, the values of the different constants being so chosen 40 that the resultant reactance of the combination being substantially the same with either value of the inductance but the effective resistance of the combination being much greater at the second value of the inductance than at the first.

6. The combination in a signaling system of an arc generator, an absorption circuit and a signaling circuit associated therewith and a single control means for simultaneously varying in opposite senses the effective resistance of each of the two circuits.

7. A radio signaling system comprising an antenna which is resonant to a desired frequency supplied by a source of radio frequency continuous current and having associated therewith a secondary circuit which comprises a variable inductance and a series capacity and a third circuit which 55 comprises the variable inductance, and a

shunt capacity, the second circuit being so proportioned that it becomes resonant to the desired frequency at one value of the variable inductance and the third circuit being so proportioned that it becomes resonant 70 to the desired frequency at a second value of the variable inductance, the values of the different constants being so chosen that the resultant reactance of the combination being substantially the same with either 75 value of the inductance but the effective resistance of the combination being much greater at the second value of the inductance than at the first.

8. The combination in a signaling system of an arc generator, an absorption circuit and a signaling circuit associated therewith and a single control means for simultaneously increasing the effective resistance 80 of the absorption circuit and decreasing the effective resistance of the signaling circuit.

9. The method of operating a radiating antenna system comprising a variable inductance which is common to two oscillating circuits which consists in varying the value of said inductance and thereby producing a substantial variation in the effective resistance of the system and at the same time maintaining the reactance of the system substantially constant.

10. The combination in a radio signaling system of an antenna supplied by a source of continuous radio frequency current, an iron core inductance in series in said antenna circuit, a similar inductance in shunt to a capacity in said antenna circuit and means for varying the saturation of the cores of said inductances in such a way as to simultaneously vary both the inductive and capacity impedance of the antenna circuit.

11. The combination in a radio signaling system of an antenna supplied by a source of continuous radio frequency current, a series inductance in said antenna circuit having a normally saturated magnetic core, a second inductance in shunt to a capacity in said antenna circuit, said second inductance having a normally unsaturated iron core and means for simultaneously varying the saturation of the cores of said inductances to simultaneously vary both the inductive and capacity impedance of the antenna circuit.

12. The combination in a radio signaling system of an antenna supplied by current from an oscillating arc system, a series inductance in said antenna circuit having a normally saturated magnetic core, a second inductance in shunt to a capacity in said antenna circuit, said second inductance having a normally unsaturated iron core and means for simultaneously desaturating the core of the first inductance and saturating the core of the second inductance.

13. The combination in a radio signaling system of an antenna supplied by current 130

from an oscillating arc system, a series inductance in said antenna circuit having a normally saturated magnetic core, a second inductance in shunt to a capacity in said antenna circuit, said second inductance having a normally unsaturated iron core and means for simultaneously desaturating the core of the first inductance and saturating the core of the second inductance, said second inductance being so proportioned that when its core is saturated it will neutralize the capacity which it shunts.

14. The combination in a radio signaling system of an antenna circuit supplied by a source of continuous radio frequency current, said antenna circuit comprising two parts, one of which has a resultant inductive impedance and the other a resultant capacity impedance and means for simultaneously varying by means of a controlling current the characteristics of said parts of the circuit in such a way that the change in effective inductive impedance of the first part neutralizes the change in the effective capacity impedance of the second part.

15. The method of controlling the flow of current in an oscillating circuit which comprises two parts, one of which has a resultant inductive impedance and the other a resultant capacity impedance which consists in varying simultaneously by means of a controlling current the characteristics of said parts of the circuit so that the change in effective inductive impedance of the first part neutralizes the change in the effective capacity impedance of the second part.

16. The method of controlling the flow of current in an antenna circuit which comprises an iron core inductance which consists in varying the permeability of said iron core and thereby varying the effective resistance of the antenna circuit while maintaining its natural frequency substantially constant.

45 17. The combination in a radio signaling system of an antenna supplied by a source of continuous radio frequency current, an iron core inductance included in the antenna circuit and means for varying the permeability of said iron core and thereby varying the effective resistance of the antenna while maintaining the natural frequency of the antenna circuit substantially constant.

55 18. The combination in a radio signaling system of a source of continuous radio frequency current, a signaling circuit and an absorption circuit associated therewith, and means for simultaneously varying in opposite senses one of the constants of each of the two circuits while maintaining the natural frequency of the system substantially constant.

65 19. The method of operating a signaling system comprising an arc generator which consists in impressing a signaling current

from said generator upon an absorption circuit and a signaling circuit and simultaneously varying in the opposite sense by a common control means one of the constants of each of the two circuits.

70 20. The method of operating a signaling system which consists in impressing a signaling current upon an absorption circuit and a signaling circuit and simultaneously varying in opposite senses one of the constants of each of the two circuits, and at the same time maintaining the natural frequency of the system substantially constant.

75 21. The method of operating a signaling system comprising an arc generator which consists in impressing a signaling current from said generator upon an absorption circuit and a signaling circuit and simultaneously varying in opposite senses by a common control means one of the constants of each of the two circuits to such an extent as to substantially prevent the flow of current in the absorption circuit during the signaling periods and to substantially prevent the flow of current in the signaling circuit during the intervals between signals.

80 22. The method of operating a signaling system comprising an arc generator which consists in impressing a signaling current from said generator upon an absorption circuit and a signaling circuit and simultaneously varying in opposite senses by a common control means one of the constants of each of the two circuits to such an extent as to substantially prevent the flow of current in the signaling circuit during the intervals between signals.

85 23. The method of operating a signaling system which consists in impressing a signaling current upon an absorption circuit and a signaling circuit and simultaneously varying in opposite senses the effective resistances of each of the two circuits and at the same time maintaining the natural frequency of the system substantially constant.

90 24. The method of operating a signaling system which consists in impressing a signaling current upon an absorption circuit and a signaling circuit and simultaneously increasing the effective resistance of the absorption circuit and decreasing the effective resistance of the signaling circuit and at the same time maintaining the natural frequency of the system substantially constant.

95 25. In a radio telegraphy transmission system, a source of oscillations, a radiating circuit containing inductance connected to said source, a shunt oscillatory circuit containing inductance connected around said source, means for varying the resistance of the radiating circuit, and means for varying the resistance of the shunt circuit in response to the operation of the radiating circuit resistance varying means.

100 26. In a radio telegraphy transmission

- system, a source of oscillations, a radiating circuit connected to said source, a shunt oscillatory circuit connected around said source, means for varying the resistance of the radiating circuit so as to alter substantially its ability to respond to the oscillations of the source, and means for varying the resistance of the shunt circuit in response to the operation of the radiating circuit resistance varying means, the variation in the shunt circuit being such as to alter the ability of the shunt circuit to respond to the oscillations of the source in a sense opposite to the alteration of the radiating circuit.

27. In a radio telegraphy transmission system having an arc for producing oscillations and a radiating circuit adapted to be supplied by the arc, means for signaling comprising means for varying a characteristic of the radiating circuit such that there is a tendency to vary the energy loss in the radiating circuit, a by-pass circuit, and means for varying the characteristics of this

by-pass circuit in response to the variation in the radiating circuit whereby the arc oscillates substantially entirely on one or the other of said circuits.

28. The combination with a source of oscillatory currents, of a tuned work circuit connected to be energized therefrom, a tuned absorbing circuit connected in shunt to said work circuit, each of said circuits including a damping device, and a single means operable to vary in opposite directions the proportions of said damping devices.

29. In an electrical system, a normally oscillatory work circuit, means included therein adapted to render the same non-oscillatory, a normally oscillatory idling circuit including means adapted to render the same non-oscillatory, and a single means operable to render one of said means effective and the other of said means non-effective, and vice versa.

In witness whereof, I have hereunto set my hand this 2nd day of May, 1918.

ERNST F. W. ALEXANDERSON.
